UNITED STATES PATENT OFFICE.

GEORGE GIFFORD PALMER, OF NEW YORK, N. Y.

TOBACCO-PIPE.

SPECIFICATION forming part of Letters Patent No. 606,473, dated June 28, 1898.

Application filed June 18, 1897. Serial No. 641,244. (No model.)

To all whom it may concern:

Be it known that I, GEORGE GIFFORD PALMER, residing at No. 408 West Twenty-eighth street, New York city, in the county of New York and State of New York, have invented certain new and useful Improvements in Tobacco-Pipes; and I do hereby declare the following to be a full, clear, and exact description of the invention, such as will enable others skilled in the art to which it appertains to make and use the same.

This invention relates to improvements in tobacco-pipes, the object of the same being to provide a tobacco-pipe in which the saliva that collects in the stem and induces the formation of nicotine is drawn away from the smoke-passage and may be blown out of the same adjoining the bowl after removing a cap which closes the end of said passage, provision being made for automatically closing the draft-tube which leads directly from the bowl when blowing the saliva from the stem.

Having the above objects in view, the invention consists of a tobacco-pipe comprising in its construction a curved stem and a mouthpiece the bore of which is enlarged, a valved tube extending from the draft-opening of the bowl, and a cap fitting over an opening in the inner end of the curved stem, as hereinafter fully described in the following specification and particularly set forth in the appended claims.

In the accompanying drawings, forming part of this specification, Figure 1 is a side elevation of a tobacco-pipe constructed in accordance with my invention. Fig. 2 is a longitudinal sectional view. Fig. 3 is an enlarged detail view of the inner tube or smoke-passage, showing the particular construction of the valve which closes the outlet-opening thereof.

Referring more particularly to the drawings, the numeral 1 designates the bowl of the pipe, which is provided in one side with the usual draft-opening 2, and rigidly attached to this bowl or formed integral therewith on a line with the draft-opening is the curved stem 3, having a bore 4 of large diameter and formed at its end with a threaded socket 5, in which fits the inner threaded end of the mouthpiece 6, the latter also having a large bore. The inner end of the stem proper

extends downward on a line with the bottom of the bowl, forming an outlet 7 for the bore, which is covered by a cap 8, fitting over a threaded projection of the stem. Within the stem is located a tube 9, communicating with the draft-opening 2 of the bowl and extending forwardly through the stem, terminating a suitable distance from the outer end of the mouthpiece, the end of said tube being closed near the end of the smoke-tube 9. In the upper part of the same is formed an opening 10, forming the communication between the said tube and pipe-stem, and this opening is normally closed by means of a valve or flap 11, having arms 12, which straddle the tube and are pivoted thereto.

A pipe constructed in accordance with my invention as herein shown and described forms one in which the smoke which is drawn from the bowl passes through the tube and up out of the opening 10 into the stem, from which it passes to the mouth of the smoker, and any saliva or spittle that may accumulate in the stem, caused by the tobacco irritant, will pass to the lower end of the stem and away from the mouthpiece, thereby preventing the formation of nicotine caused by any excess of moisture.

In order to clean the stem, it is only necessary to remove the cap 8 and blow into the stem, which will force the saliva out of the opening 7, the valve closing to prevent the draft going into the bowl.

From this it will be seen that I provide a pipe in which the formation of nicotine is entirely obviated and one in which the cleaning of the pipe is readily effected without disturbing the contents of the bowl. It will also be observed that the construction does not materially increase the size of the stem, but greatly adds to the comfort of the smoker.

Having thus described the invention, what is claimed as new, and desired to be secured by Letters Patent, is—

1. A tobacco-pipe comprising a bowl having a draft-opening, a stem, a tube located within said stem and communicating with the draft-opening, and through a similar opening with the interior of the stem, and a valve for controlling the opening in said tube.

2. A tobacco-pipe comprising a bowl having a draft-opening, a stem for the bowl having

an opening adjoining the bowl communicating with the outside, means for closing the opening in said stem, a tube located within said stem communicating with the draft-opening, closed at its outer end, and provided with an opening in its upper side, and a valve for the opening in said tube.

3. A tobacco-pipe comprising a bowl having a draft-opening therethrough, a curved stem secured to said bowl provided with an opening adjoining the bowl and communicating with the outside, a cap for closing said opening, a tube located within said stem communicating with the draft-opening, closed at its outer end, and having an opening in its upper side, and a gravity-valve for closing the opening in said tube, as and for the purpose set forth.

4. A tobacco-pipe comprising a bowl having a draft-opening therein, a stem for the bowl,

25 said stem being curved, and a mouthpiece connected to the stem, the latter having an opening at or adjoining the bowl which is closed by a removable cap; together with a tube located within the stem and communicating with the draft-opening of the bowl, said tube being closed at its outer end and provided with an opening in its upper side, and a valve or flap closing the opening in the draft-tube, the parts being constructed and arranged substantially as shown and described.

30 In testimony whereof I have signed this specification in the presence of two subscribing witnesses.

GEORGE GIFFORD PALMER.
